[57] CLAIM

The ornamental design for a vehicle brushguard, as shown.

DESCRIPTION

FIG. 1 is a perspective view of the vehicle brushguard showing my new design;

FIG. 2 is a side elevational view thereof;

FIG. 3 is a top plan view thereof;

FIG. 4 is a front elevational view thereof;

FIG. 5 is a bottom plan view thereof; and,

FIG. 6 is a rear elevational view thereof.

The broken line showing of mounting brackets are for illustrative purposes only and forms no part of the claimed design.
